CLAIM

The ornamental design for a carrier for containers as shown and described.

DESCRIPTION

FIG. 1 is a rear, top perspective view of a carrier for containers showing my new design, shown in a folded configuration.

FIG. 2 is a front, bottom perspective view of the carrier of FIG. 1.

FIG. 3 is a front elevation view of the carrier of FIG. 1. FIG. 4 is a right elevation view of the carrier of FIG. 1; the left elevation view is a mirror image of the right elevation view.

FIG. 5 is a rear elevation view of the carrier of FIG. 1.

FIG. 6 is a top plan view of the carrier of FIG. 1.

FIG. 7 is a bottom plan view of the carrier of FIG. 1; and, FIG. 8 is a plan view of the carrier of FIG. 1 shown in an unfolded configuration.

The broken lines are shown for the purpose of illustrating both parts of the article as well as environmental subject matter. None of the broken lines form part of the claimed design.

1 Claim, 8 Drawing Sheets
